Primary Examiner — Thomas Johannes(74) *Attorney, Agent, or Firm* — Sutherland Asbill and Brennan LLP**(57) CLAIM**

The ornamental design for a container with a castle-shaped base, as shown and described.

DESCRIPTION

FIG. 1 is a side view of a container with a castle-shaped base according to a first embodiment;

FIG. 2 is a bottom view thereof;

FIG. 3 is a top view thereof; and,

FIG. 4 is a forward lower perspective view thereof.

The broken lines are directed to environment and show unclaimed subject matter only; the broken lines form no part of the claimed design.
